UNITED STATES PATENT OFFICE.

WILLIAM GRIMSHAW, OF GLEN ELLYN, ILLINOIS.

STRUT FOR AUTOMATIC SPRINKLERS.

Application filed August 25, 1923. Serial No. 659,294.

This invention relates to struts for automatic sprinklers used for securing the caps or valves of the sprinklers in closed position, and relates particularly to struts of the toggle type.

The invention also relates to an improved process of producing struts of the type specified.

As the invention relates to the article, the object of the invention is to provide an improved strut of the type specified, which will be relatively many times stronger than struts now commonly used, all of which will be facsimiles of one another, both as regards shape, size and resistance to withstand stresses, and which may be produced in quantities at relatively very small cost.

As the invention relates to a process of manufacture, the object of the invention is to provide a practical process for producing struts possessing the foregoing characteristics, whereby said struts of relative great strength may be produced in quantities at relatively very small cost as compared with present methods of manufacture.

To effect the objects of the invention my improved process consists in punching blanks from suitable sheet metal, and in shaping said blanks to the form of the finished article by successive swaging operations in progressively conforming dies; and as the invention relates to an article of manufacture, I attain the object of the invention by subjecting a suitable blank to the various steps or operations which constitute my improved process.

In the accompanying drawing, in which the steps or operations comprising my improved process and the finished strut members resulting therefrom are illustrated,

Figure 1 is a diagrammatic view showing a strut of the general type to which my invention relates, as applied in use for securing the cap or valve of the sprinkler in closed position.

Figure 2 is a side view of the female member of a strut embodying my invention and improvements.

Figure 3 is an end view thereof from the left side of Fig. 2.

Figures 4 and 5 are views corresponding to Figs. 2 and 3, of a blank suitable for the production of said strut member by the practice of my improved process.

Figures 6 and 7 are corresponding views

showing said blank after being subjected to the first swaging operation.

Figures 8 and 9 are corresponding views showing said blank after being subjected to the second swaging operation; and

Figures 10 and 11 are similar views showing the blank after being subjected to the third swaging operation.

Referring now particularly to Fig. 1 of the drawing, in which I have, for purposes of clear and definite illustration, shown a strut of the general type to which the present invention relates, as applied in use for securing the cap or valve of the water nozzle of an automatic sprinkler in closed position, ⁶⁵ *a* designates the base portion of the sprinkler frame, *a*¹ the arms thereof which connect said base portion with the abutment *a*², *a*³ the valve or cap which closes the water discharge nozzle of the sprinkler, *a*⁴ a stressing screw having threaded engagement with a hole formed through the abutment *a*², *a*⁵ and *a*⁶ articulated male and female strut members inserted between the cap or valve *a*³ and the inner end of the stressing screw *a*⁴, ⁷⁰ the remote ends of said strut members being rounded and engaging recessed seats or bearings formed in the valve cap *a*³ and in the end of the stressing screw *a*⁴, respectively, and *a*⁷ a fusible link which connects the ⁷⁵ ends of the lever arms forming parts of the strut members *a*⁵, *a*⁶. In the drawings, the strut members *a*⁵, *a*⁶ are shown in full lines and all other parts of the sprinkler in dotted lines. ⁸⁰

As regards its usual features and excepting as hereinafter particularly described and pointed out, said sprinkler may be of any usual or approved construction, and will readily be understood by persons skilled in the art from an examination of the drawings, without a description thereof in detail. ⁸⁵

In accordance with my improved process of manufacture, the strut members *a*⁵, *a*⁶, are formed from blanks punched from a ⁹⁰ plate of suitable ductile sheet metal—preferably phosphorbronze—substantially .128 of an inch in thickness.

In Figs. 4 and 5 of the drawings, I have shown a blank, designated as a whole *a*⁸, ⁹⁵ adapted for making either the male strut member *a*⁵ or the female member *a*⁶, said blank comprising a portion 1 adapted for forming the strut portion proper of said strut member, and an arm portion 2. ¹⁰⁰

In accordance with my improved process, the blanks a^8 are wrought to the form of the finished strut members a^5 , a^6 , by subjecting them to four successive forging or 5 swaging operations in dies which progressively conform to the shape of said strut members. As a result of extended tests and experiments, I have discovered that said blank can be brought to final shape by four 10 different swaging operations performed on said blank in succession, the first of said operations imparting to the blank substantially the shape shown in Figs. 6 and 7, the second swaging operation imparting to said blank 15 the shape shown in Figs. 8 and 9, the third operation imparting to the blank the shape shown in Figs. 10 and 11, and the fourth and final forging operation conforming said blank to the shape of the finished strut member, as the female member shown in Figs. 2 and 3.

By means of my improved process of manufacture, I am able to produce strut members a^5 , a^6 , in large quantities, all of 25 which will be fac similes of one another; which will be relatively many times stronger than struts of the same general type produced by present methods of manufacture, and the cost of which is relatively very much 30 less.

Struts made in accordance with my improved process possess a great advantage over struts made in any other manner of which I have any knowledge, in the respect 35 that, due to the forging and swaging to which they are subjected in manufacture, they are much stronger than other struts, first, because they are rendered very tough by said forging and swaging operations, 40 second, because said operations compact and consolidate the surface of the metal, rendering it very dense and imparting to it great strength and resistance to withstand the stresses which it will sustain in use, and 45 third, because, due to the process of manufacture, the struts are finished complete by the forging and swaging operations to which they are subjected, without a separate finishing operation, thus materially reducing the 50 cost of production of said struts.

Having ascertained by test and experiment the form of the blank most desirable for use in the manufacture of the strut members in accordance with my improved process, the number of forging operations to be employed 55 and, in a general way the successive shapes to which the blanks are to be wrought, skilled mechanics can readily produce conforming dies suitable for performing the different steps of my improved process of 60 manufacture and it will not, therefore, be necessary to either show or describe said dies in detail.

I claim—

1. The process of making struts for automatic sprinklers, which consist in punching blanks substantially of the shape shown in Figs. 4 and 5 from suitable sheet metal, subjecting the portion 1 of said blank to a swaging operation in the directions indicated by 65 the arrows, Fig. 4, bringing it substantially to the form shown in Figs. 6 and 7, subjecting the entire blank to a swaging operation in the directions indicated by the arrows, Fig. 6, bringing it substantially to the form 70 shown in Figs. 8 and 9, subjecting the entire blank to a swaging operation in the directions indicated by the arrows, Fig. 9, bringing it substantially to the form shown in Figs. 10 and 11, and in then subjecting the 75 entire blank to a swaging operation in the directions indicated by the arrows, Fig. 10, bringing it substantially to its final form shown in Figs. 2 and 3, each swaging operation being substantially at right angles to 80 the last preceding operation whereby fins or ribs formed on the blank in earlier swaging operations will be obliterated by later swaging operations and said struts wrought to final form without a separate finishing 85 operation.

2. The process of making struts for automatic sprinklers as specified in claim 1, in which the dimension of the blank transversely to the line of impact is increased at 90 each swaging operation.

In witness that I claim the foregoing as my invention, I affix my signature this 16 day of August, A. D. 1923.

WM. GRIMSHAW.
